AKTIENGESELLSCHAFT, OF WOHLLEN, SWITZERLAND

METHOD OF AND MACHINE FOR SHAPING HAT BRAID

Application filed March 30, 1931, Serial No. 526,449, and in Switzerland September 29, 1930.

This invention relates to an improved method of and machine for shaping braids, usually made of straw, used in the manufacture of hats.

5 Such braids are placed on the market, for use by hat manufacturers, in comparatively narrow widths, the strands of the braid being closely woven, and special machines are provided for widening the braids before they 10 are made up into hats, according to requirements. These machines consist substantially of two pairs of rollers, the first pair being feed rollers with a roughened surface, also called thrust rollers, while the second pair 15 consists of a press roller and a heated drum. The first pair of rollers pushes the braid between the second pair at a greater speed than the latter can take it in and thereby causes the braid to widen, in which operation 20 the strands of braid are caused to separate and this gives the braid simultaneously a certain ornamental configuration.

The main object of this invention now is to provide a means whereby the braid is not 25 only widened but also twisted, which increases the ornamental effect of the widened braid.

Another object of the invention is to provide a machine for performing the above 30 mentioned operation in a simple, effective, and inexpensive manner.

Other objects of the invention consist in the particular construction, combination and arrangement of parts more specifically set 35 forth hereunder and illustrated in the accompanying drawing in which

Fig. 1 is a side elevation and Fig. 2 a front view of a machine constructed according to this invention.

40 Fig. 3 is a detail elevational view of a part of the machine and Fig. 4 is an end view of the part shown in Fig. 3.

Fig. 5 is a detail plan view of another part 45 of the machine and Fig. 6 is a reverse cross sectional view of the same.

Figs. 7 and 8 are, respectively, fragmentary side and front elevational views of still another part of the machine.

Fig. 9 is a fragmentary elevational view 50 of a braid partly in its original narrow shape

and partly in its widened and twisted shape.

Referring to the drawing by numerals, a main frame 10 carries, rotatably mounted therein, a V-pulley 11 adapted to be driven from any suitable source of power. A rearward projecting portion 11a of the pulley has a cam groove 11b provided in it which co-acts with a pinion 12 adapted to travel therein, secured to one end of a lever 14 pivotally mounted on a pinion 13, and a connecting rod 15 secured to the other end of the lever 14, to reciprocate a rocker arm 17 pivotally mounted to the frame 10, as shown at 16. The upper end of the rocker arm 17 is provided with a toothed segment or rack 17a which meshes with a pinion 18 carried by a guide socket 19 rotatably mounted in the frame 10. A set screw 20 co-acts with an annular groove 21 provided in the guide socket 19 to prevent longitudinal movement 20 of the same. A rectangular slot 22 is provided through the center of the guide socket 19 for the purpose of inserting therein and guiding the comparatively narrow braid 23 as furnished in commerce. The rear end of 25 the guide socket 19 is conically shaped so as to allow it to come into close proximity of the pair of thrust rollers 24 between which the braid 23 is fed through the slot in the guide socket 19. The distance of the thrust 30 rollers 24 from each other may be regulated by a screw 25 to allow the feeding through the thrust rollers of braid of different thicknesses.

By the rotation of the pulley 11 and the cam 35 member 11a associated therewith, the rocker arm 17 is caused to rotate the pinion 18 and thereby the guide socket 19 alternately in one direction and the other, i. e. clockwise and counter-clockwise, by a half turn each time, 40 thus twisting the braid 23 as it is fed between the thrust rollers 24, from one side to the other. The result is shown in Fig. 9. It will be understood that the number of reciprocating movements in a given time may be 45 regulated by the speed of the pulley 11 or the configuration of the cam groove 11b or both with relation to the speed of feeding the braid so that thereby the length of braid between its twisted portions can be 50

made greater or smaller, resulting in different shapes of the braid between twists, such as elliptical, oval or almost round.

The twisted but still narrow braid on leaving the thrust rollers 24 is thrust into a stationary guide consisting of an upper plate 31 and a lower plate 32 and intermediate spacing strips 33 between the same, which are so shaped that they form a passage 34 for the braid, the front part of which is narrow and gradually widens out. After the braid passes through this passage 34, it is engaged between a press roller 35 and a heated drum 36 on which latter it is partly wound and then leaves the machine over an idler 37.

The thrust rollers 24 are caused to rotate at a greater peripheral speed than the press roller 35 and thereby the braid is forced to widen out in the stationary guide passage 34.

The drum 36 is driven by friction only corresponding to the speed of the press roller 35. The upper thrust roller 24 is rigidly mounted on a shaft 26 driven by a gear 27 from any suitable source of power. The shaft 26 also carries a gear 28 meshing with a gear 29 carried by a countershaft 30 on the other end of which is mounted the lower thrust roller 24.

It will be understood that V-pulleys of different sizes or with different cam grooves may be provided for the same machine to be alternately used with the same, in order to change the distance of the twisted portions of the braid from each other as previously described.

It is understood that while I have thus described a preferred form of embodiment of my invention, I do not wish to be limited to the mechanical details shown and described, but may resort to such modifications and alterations as come within the scope of the claims hereinto appended.

I claim:

1. A machine for shaping hat braid comprising, in combination, two sets of rollers rotating at different peripheral speeds and means for guiding hat braid between one pair of said rollers, said means alternately turning said braid from one side to the other so as to twist it at regular spaced portions of same.

2. A machine for shaping hat braid comprising, in combination, two sets of rollers rotating at different peripheral speeds, means for guiding hat braid between the first set of said rollers, said means turning said braid alternately from one side to the other and means between said two sets of rollers for widening said braid after twisting in a continuous operation.

3. A machine for shaping hat braid comprising, in combination, a frame, a pair of thrust rollers, carried by said frame, a press roller and drum carried by said frame in

spaced relation to said thrust rollers, said thrust rollers being driven at a greater peripheral speed than said press roller and drum, and a guide socket rotatably mounted in said frame, adapted to be rotated alternately clockwise and counter-clockwise, and having means for guiding hat braid through it, substantially as and for the purpose set forth.

4. A machine for shaping hat braid comprising, in combination, a frame, a pair of thrust rollers for feeding hat braid, carried by said frame, a press roller and drum carried by said frame in spaced relation to said thrust rollers, said thrust rollers being driven at a greater peripheral speed than said press roller and drum, a guide socket rotatably mounted in said frame, means for preventing longitudinal movement of said guide socket and means for rotating said guide socket so as to twist the hat braid fed through it.

5. A machine for shaping hat braid comprising, in combination, a frame, a pair of thrust rollers, carried by said frame, a press roller and drum carried by said frame in spaced relation to said thrust rollers, said thrust rollers being driven at a greater peripheral speed than said press roller and drum, a guide socket rotatably mounted in said frame, a pinion mounted on said guide socket, a rack adapted to rotate said pinion alternately in one direction and the other, and means for reciprocating said rack at predetermined intervals.

6. A machine for shaping hat braid comprising, in combination, feeding means for hat braid, guiding means for said hat braid adapted to twist it before it is engaged by said feeding means and means for widening said hat braid after twisting, in one continuous operation.

In testimony whereof I affix my signature.

ALBERT KOCH.
